A detailed technical cross-sectional diagram of a mechanical assembly, possibly a pump or valve mechanism. The diagram shows a complex arrangement of parts including a central vertical rod (100), a piston (80), a connecting rod (78), a crankshaft (79), and various gears and shafts. Numerous components are labeled with numbers such as 19, 30, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, and 103. The diagram uses lines to connect labels to specific parts, indicating their locations and relationships within the assembly.

CARTON FOLDING MACHINE

William H. Inman, Newark, N. Y., assignor to
Bloomer Bros. Company, Newark, N. Y., a corpora-
tion of New York

Application August 9, 1946, Serial No. 689,415

16 Claims. (Cl. 93—49)

1 This invention relates to machines for folding blanks of cardboard or other sheet material to form containers or cartons, one object of the invention being to provide a machine adapted for folding a one piece blank to form a fluid tight carton of the variety having side walls continuously connected at their corners by integral flaps folded to overlap in pairs against opposite side walls and interlock with each other, to maintain the carton in erected shape, substantially as disclosed, for example, in my copending patent application, Serial No. 567,489, filed December 9, 1944, which has matured into Patent No. 2,419,646.

Another object of the invention is to provide an efficient machine of the above character capable of reliably folding and securing such cartons in erected shape at a rapid and economical rate.

A further object is to provide a machine of the above character having a simple and practical type of construction conveniently adapted to receive the blanks and deliver the erected cartons.

To these and other ends the invention resides in certain improvements and combinations of parts, all as will be hereinafter more fully described, the novel features being pointed out in the claims at the end of the specification.

In the drawings:

Fig. 1 is a top plan view of a machine embodying the present invention with the parts shown in position to receive a carton blank;

Fig. 2 is an end elevation of the machine as viewed from the left in Fig. 1;

Fig. 3 is a fragmentary view of the carton handling parts shown in Fig. 2 with a carton blank applied thereto;

Fig. 4 is a top plan view of parts shown in Fig. 3, including the blank to be folded;

Fig. 5 is a perspective view of a carton folded by the machine;

Fig. 6 is an enlarged top plan view similar to Fig. 4, but showing the carton partly folded;

Fig. 7 is an end elevation, partly broken away, as seen from the left in Fig. 6;

Fig. 8 is a top plan view, partly broken away, similar to Fig. 6, but showing the carton in a further stage of folding;

Fig. 9 is an end elevation as viewed from the left in Fig. 8;

Fig. 10 is a view similar to Fig. 9, but showing further folding of the carton;

Fig. 11 is a top plan view showing the final folding steps;

Fig. 12 is an enlarged sectional elevation on the line 12—12 in Fig. 1;

2 Fig. 13 is an end elevation as viewed from the left in Fig. 11;

Fig. 14 is a sectional elevation showing the folded carton ready for removal from the machine;

Fig. 15 is a side elevation substantially as seen from the left in Fig. 9 and showing the driving mechanism;

Fig. 16 is a view similar to Fig. 15 substantially as seen from the right in Fig. 9;

Fig. 17 is a sectional elevation on the line 17—17 in Fig. 15, showing the mechanism for operating one of the blank folding wings;

Fig. 18 is a view similar to Fig. 17 on the line 18—18 in Fig. 15, but showing the mechanism for operating the blank folding fingers;

Fig. 19 is a similar view on the line 19—19 in Fig. 15, but showing mechanism for operating the other blank folding wing, and

Fig. 20 is a similar view on the line 20—20 in Fig. 15, showing mechanism for operating the blank folding arms.

The invention provides a machine particularly adapted for erecting a carton such as disclosed in my said patent application and here illustrated as a blank in Fig. 4 and in erected condition in

Fig. 5, comprising a bottom 30 and upwardly folded pairs of opposite side walls 31 and 32 and 33 and 34. The adjacent side walls at each corner of the box are integrally connected by folded corner webs or flaps 35 to 38, inclusive, which are each folded medially as at 39. Flaps 36 and 37 have on their outer walls top extensions 40 and 41 which are folded over inwardly and downwardly

between the flaps and the adjacent side walls 31 and 32, the lines of fold having therein slots 42 adapted to receive and interlock with hooks 43 formed at the tops of the inner walls of the other corner flaps 35 and 38, respectively. Each hook 43 has an undercut edge 44 which snaps over the end of the corresponding slot 42, so as to interlock the flaps 35 and 36 and 37 and 38 together in pairs and securely hold the carton in erected position. A fluid tight carton is thus provided with bottom and side walls having continuous, folded, leakproof connection with each other below the plane of its top filling opening which is provided with suitable closure flaps, as shown.

The embodiment of the invention herein disclosed, by way of illustration, comprises, preferably, a frame having a base 45, Figs. 1 and 2, supporting opposite end pedestals 46 on which the various parts are mainly supported. The lower portions of the pedestals are formed with bearings 47 supporting the end portions of an

oscillating driving shaft 48, hereafter more fully described. Fixed on and connecting the upper ends of the pedestals is an elongated, table-like support 49 for receiving and supporting the bottom portions 30 of the carton blank, as shown in Figs. 3 and 4.

For folding upwardly the opposite sides 33 and 34 of the blank, support 49 carries pairs of hinge leaves 50-51 and 52-53 at its opposite sides, respectively, the knuckles of which rotatably support a pair of spindles 54 and 55 extending parallel with each other along the opposite sides of support 49, as shown. A pair of wings 56 and 57 are mounted on the spindles, respectively, for oscillating movement from the substantially horizontal, blank receiving position shown in Fig. 1, up to and somewhat beyond a vertical position, as shown in Fig. 9, each wing having for this purpose a plurality of knuckles rotatably embracing its spindle. The wings are raised and lowered by mechanism connected therewith, and the spindles 54 and 55 are separately oscillated for actuating certain other parts, as hereafter described.

Wing 57, for raising carton wall 34, has brackets 58 fixed on its opposite ends and supporting a pair of plates each having an edge turned to provide an elongated abutment 59, Figs. 1 to 3, inclusive, in fixed relation with the wing. Wing 57 is provided also along its free edge with three spaced guides 60, 61, and 62, Fig. 1, in the form of U-shaped clips each fixed at one end (Fig. 15) to the back of the wing and having its other end projecting around over the upper face of the wing in spaced relation thereto, to receive and position one edge of the blank, as shown in Fig. 4. Guides 60 and 62 carry curved finger extensions 63 and 64 for guiding the blank to position. Wing 56 has a pair of upstanding guide brackets 65 at its outer edge to locate and hold the opposite edge of the blank, as shown in Fig. 4.

It is evident from the above construction that a blank may be readily slid into place on support 49 and its wing extensions 56 and 57, with one edge of the blank under the guides 60 to 64, inclusive, of wing 57, its bottom section resting on support 49 and its opposite edge against guides 65 on wing 56, as shown in Fig. 4. The blank is preferably first scored along its folding lines and "broken" along such lines to condition it for proper folding, as well understood in the art. The abutments 59 on wing 57, extending upwardly somewhat above the top surface of the wing and under the corner fold flaps 36 and 37, support these corner folds and the side walls 31 and 32 at an initial upward inclination to insure proper folding of such parts when the wings 56 and 57 are raised.

Wing 57 has fixed thereon a bracket 66, Fig. 17, pivotally connected with one end of a link 67, the other end of which is pivotally connected with a lever 68 which is rocked by the operating mechanism hereafter described, to raise and lower the wing. Wing 56 has fixed thereon a bracket 69, Fig. 19, pivotally connected with one end of a link 70, the other end of which is pivoted to a lever 71, which is rocked by mechanism hereafter described, to swing the wing in timed coordination with wing 57, so that the wings are raised from the substantially horizontal position shown in Fig. 2 to the upwardly inclined position shown in Fig. 7 and eventually to the position shown in Fig. 9 in which they are inclined somewhat inwardly toward each other. During such movement, the wings fold the side walls 33 and

34 upwardly and fold the corner folds outwardly, thereby folding the side walls 31 and 32 upwardly, assisted by the pressure of the abutments 59 on wing 57, so as to position the parts of the blank as shown in Figs. 8 and 9. The final inward inclination of the wings 56 and 57 tends to compress the carton and bulge the side walls 31 and 32 inwardly as indicated at 72, Fig. 8, thereby tending to incline the tops of the corner folds inwardly and downwardly, when in their fully folded position against the side walls, to assist in engaging them with each other, as more fully described hereafter.

The means for folding inwardly, engaging and interlocking the corner flaps with each other in pairs, comprises preferably a pair of rounded tucking fingers 73, Figs. 1, 9, 11, and 15, one at each end of wing 57 and fixed on the opposite ends of a shaft 74 rotatably mounted in bearings 75 on the under-side of the wing. Fixed on shaft 74 is a pinion 76, Fig. 11, meshing with a spur gear 77 fixed on a short shaft 78 journaled in bearings 79 on the wing. Fixed on shaft 78 is an arm 80, Figs. 11 and 15, pivotally connected with one end of a link 81 having its other end pivotally connected with one end of a link 82 pivoted at its opposite end to a lever 83 mounted to rock on the frame of the machine. Rocking of the lever, by the mechanism hereafter described, serves to oscillate gear 77 and rock the shaft 74 to swing the tucking fingers 73 from the position shown in Figs. 1 and 2, to and from the position shown in dotted lines in Fig. 10. As these fingers swing inwardly and downwardly over the corner folds 36 and 37, they engage the upper edge of the top extensions 40 and fold them inwardly and downwardly, tucking them in between the corner folds and the adjacent side walls of the carton.

As the fingers 73 descend, they press the extensions 40 and the corner folds 36 and 37 between them and the fixed abutments 59 of the wing, so as to bow the corner folds outwardly, raising and retracting the outer ends of their folded portions, as indicated at 84, Fig. 10, in slightly spaced relation with extensions 40, thus positioning these corner folds, and their in-folded extensions 40, to receive between them the cooperating corner folds 35 and 38 which are folded inwardly for that purpose by means which will now be described.

The means for completing the inward folding and interlocking of the corner folds 35 to 38, inclusive, comprises swinging arms preferably mounted at the opposite ends of both wings 56 and 57. Referring first to wing 56, such arms are shown at 85, Figs. 9, 10, and 16, pivotally mounted on spindles 86 supported on the under sides of the opposite ends of wing 56 and extending transversely to the pivotal axis of the wing. Fixed stops 87 limit the outward movement of the arms to a position in which they are inclined somewhat upwardly in the horizontal position of the wing, as shown in Fig. 2, to assist the abutments 59 in initially positioning the blank in the machine as described above. Actuating means are provided for the arms 85, operated after the fingers 73 have positioned the corner folds 36 and 37, as described and as shown in Fig. 10, to press the arms 85 and corner folds 35 and 38 inwardly so as to engage the ends of the folds between the corner folds 36 and 37 and their downward extensions 40. Such actuating means preferably comprises a pair of fingers 88, Figs. 1, 7, 9, and 13, fixed on the opposite ends of the

Spindle 54 of the wing, respectively, the spindle being actuated by an extension 89 on one of the fingers, Fig. 20, pivotally connected with one end of a link 90 having its other end pivotally connected with the upper end of a lever 91 which is rocked by the operating mechanism. Means are provided for pressing inwardly, alining and interlocking the corner folds of each pair, comprising, preferably, a pair of arms 92, Figs. 1, 6, and 11, in the form of resilient arms or clips each fixed on an arm 93 pivotally mounted on the rear face of wing 57 about a pintle 94 extending transversely to the pivotal axis of the wing. Each arm 93 has a reversely bent extension 95 inclined to the active portion 92 of the arm assembly, for cooperation with a roller 96 on a spindle 97 fixed at its lower end to an arm 98, pinned to the spindle 55 on which the wing 57 is mounted. Arm 98 is pivotally connected with one end of a link 99 pivoted at its opposite end to the upper end of a lever 100 mounted on the frame and rocked by the operating mechanism. A tension spring 101, Figs. 8 and 9, is connected between the outer end of spindle 97 and a post 102 on arm 93 to hold the inclined portion 95 of the arm in contact with the roller 96.

As lever 100 is rocked by the mechanism hereinafter described, it swings both of the spindles 97, connected through the wing spindle 55, so that the rollers 97 engage and swing the arms 93 to press their resilient clips 92 against the corner folds 36 and 37, as shown in Figs. 11 and 13. At the same time or shortly before, the tucking fingers 13 are raised, as shown in Fig. 13, to free the corner folds 36 and 37, leaving them inclined upwardly, as shown in Fig. 10, while the cooperating corner folds 35 and 38 are inclined somewhat downwardly, as described. In such positions the top hooks 43 at the inner ends of the latter folds are readily engaged beneath the line of folding between the corner folds 36 and 37 and their inturned extensions 40. As the arms 92 are pressed inwardly, they straighten out the bowed folds 36 and 37, pressing the folds of each pair inwardly into substantial alinement with each other, in which position the hooks 43 enter the slots 42 at the tops of the cooperating folds, to interlock them with each other.

The several parts, including the wings 56 and 57, are then returned to initial position, releasing the pressure of the wings on the side walls 33 and 34 of the carton, whereupon the inwardly bowed walls 31 and 32 straighten outwardly and draw the hooks 43 against the ends of the slots 42. The undercut portions 42 of the hooks are thus brought to project over and wedgingly interlock with the ends of the slots and securely fasten the corner folds together and the carton in erected condition.

The remaining mechanism for operating the several parts preferably comprises the oscillating shaft 48 described above and a plurality of cams fixed thereon and each provided with a follower mechanism for operating the several parts of the machine. The shaft thus carries a cam 103, Figs. 1 and 9, coacting with a roller 104 carried by lever 100 for oscillating spindle 55 and the rollers 96 which press in the side arms 92 as described above. A tension spring 105 has one end fixed to the lever and the other end fixed to a spring supporting bar 106, Fig. 2, carried by cross arms 107 mounted on the pedestals 46 of the frame, the spring serving to hold the follower 104 in contact with the profile of the cam.

The mechanism for operating the wing 57 com-

prises preferably a cam 108, Figs. 15 and 17, fixed on shaft 48 and coacting with a roller 109 on lever 68, the roller being held in contact with the cam by means of a spring 110 fixed at one end of the lever and at the other to a bar 111 carried by the cross arms 107. As previously described, lever 68 is connected with wing 57 to swing the wing up and down under control of the cam.

The mechanism for operating the fingers 13, 10 which fold inwardly and downwardly the extensions 40 and 41 of corner folds 36 and 37, comprises preferably a cam 112 fixed on shaft 48, Figs. 15 and 18, coacting with a roller 113 on the lever 83, the roller being held in contact with the cam by means of a spring 114 fixed at one end to the lever and at the other end to the bar 111, the cam acting through the linkage and gearing already described to oscillate the shaft 74 on which the fingers are mounted.

The mechanism for operating the wing 56 for folding upwardly the carton side wall 33 comprises preferably a cam 115 on shaft 48, Figs. 15 and 19, coacting with a roller 116 on the lever 71, the roller being held in contact with the cam by a spring 117 connected at one end to the lever and at the other end to the rod 106.

The mechanism for operating the arms 85, for folding in the corner folds 35 and 38, comprises preferably a cam 118, Figs. 1 and 20, fixed on shaft 48 and coacting with a roller 119 on the lever 91 having a link and arm connection with the spindle 54 carrying the fingers 88, for actuating the arms inwardly to fold the corner folds inwardly at the proper time. A spring 120 is connected at one end with the lever and at its other end with the rod 106, the cam operating, through the connections described, to swing the wings to press in the corner folds at the proper time.

In the present embodiment operating shaft 48 is preferably rocked manually by means of a crank lever 121 and handle 122, Figs. 1, 2, and 15, the frame being preferably provided with upper and lower brackets 123 and 124 serving as stops for arresting the crank in its extreme positions. It is obvious, however, that such manual operating means may be replaced by a motor driven mechanism.

The operation of the machine has been explained in connection with the above description of its construction, from which it is evident that a blank may be readily fed to the machine so as to lie with its bottom section on support 49 and one pair of opposite side walls on wings 56 and 57, in a position accurately determined by the several locating guides. Rotary actuation of crank handle 122 then first operates to swing the wings 56 and 57 upwardly so as to fold upwardly the blank walls 33 and 34, thereby folding the corner folds about their median lines 39 to force them outwardly and force inwardly and raise the other pair of side walls, 31 and 32, to a position bowed somewhat inwardly beyond the vertical, as shown in Fig. 8. Continued rotation of the crank then causes the fingers 13 to swing inwardly and downwardly against the upper edges of the top extensions 40 and 41 of the corner folds 36 and 37, as shown in Figs. 8 and 9, so as to fold these top extensions downwardly between their corner folds and the side walls of the carton, as shown in Fig. 10. In this folding step, the flaps and their extensions are bent or bowed outwardly and somewhat raised and separated, as shown, so that in the extreme lower position of the fingers 13, shown in dotted lines in Fig. 10, the corners of the cooperating flaps 35 and 38 may be readily

entered between the flaps 36 and 37 and their in-folded top extensions. As shown in full lines, Fig. 10, the fingers are rising, allowing the flaps 36 and 37 to straighten somewhat after their folded portions have received the ends of the cooperating flaps 35 and 38.

Continued rotation of the crank swings inwardly the presser arms or clips 92, Figs. 11 and 13, to further straighten and align the engaged corner folds and insert the hooks 43 in their slots 42. On further rotation of the crank the fingers 38 and the arms 92 are retracted, the wings 56 and 57 are swung downwardly to horizontal position, releasing the carton walls 33 and 34 and allowing the walls 31 and 32 to straighten and swing outwardly, thus forcing the undercut edges of the hooks into secure locking engagement with the ends of their slots. The carton then remains with one of the closure flaps under the positioning guides 60 to 64, inclusive, resting on wing 57, as shown in Fig. 14, in condition to be readily slid out of engagement with the locating guides and removed from the machine which is then ready for repetition of the operation.

The machine is thus adapted to quickly erect the side walls with their outwardly extending corner flaps and to efficiently bend and position the corner folds for engagement one within the folded portions of the other and to interlock them securely with one another to complete the erection of the carton. The machine is adapted to readily receive the blanks as they are fed to it and presents the folded carton in convenient position for removal from the machine, the entire operation being rapidly, precisely, and accurately performed.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A machine for folding a blank to form a fluid tight carton of the type having a bottom, upwardly folded side walls, corner flaps foldably connected with adjacent side walls and folded and overlapped in pairs against the outer sides of one pair of opposite side walls, and interengaging means on said flaps, respectively, for locking the flaps of each pair together, said machine comprising a support for said carton bottom, wings mounted to swing at opposite sides of said support for folding the other pair of opposite side walls upwardly and said corner flaps outwardly and thereby folding the first mentioned side walls upwardly, devices movably mounted on said wings for moving the flaps of each pair into interlocking engagement with each other, and mechanism for operating the parts of said machine.

2. A machine for folding a blank to form a fluid tight carton of the type having a bottom, upwardly folded side walls, corner flaps foldably connected with adjacent side walls and folded and overlapped in pairs against the outer sides of one pair of opposite side walls, and interengaging means on said flaps, respectively, for locking the flaps of each pair together, said machine comprising a support for said carton bottom,

wings pivoted to swing about parallel axes on opposite sides of said support, respectively, for folding the other pair of opposite side walls upwardly and said corner flaps outwardly and thereby folding the first mentioned side walls upwardly, devices pivotally mounted on said wings to swing about axes extending transversely of the pivotal axes of said wings, for moving the flaps of each pair into locking engagement with each other, and mechanism for operating the parts of said machine.

3. A machine for folding a blank to form a fluid tight carton of the type having a bottom, upwardly folded side walls, corner flaps foldably connected with adjacent side walls and folded and overlapped in pairs against the outer sides of one pair of opposite side walls, one flap of each pair having folded portions receiving therebetween the other flap of the same pair, and interengaging means on said flaps, respectively, for locking said flaps of each pair together, said machine comprising means for folding said side walls upwardly and said corner flaps outwardly, devices for bowing the first mentioned flaps outwardly to retract and position the outer ends of said folded portions thereof to receive the ends of said other flaps, means for engaging said other flaps between the folds of the first mentioned flaps and for interlocking said interengaging means, and mechanism for operating the parts of said machine.

4. A machine for folding a blank to form a fluid tight carton of the type having a bottom, upwardly folded side walls and corner flaps foldably connected with adjacent side walls and folded and overlapped in pairs against the outer sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising means for folding said side walls upwardly and said corner flaps outwardly, devices for folding said top extensions inwardly and downwardly and for bowing the first mentioned flaps outwardly to retract and position the outer folded ends thereof to receive the ends of said other flaps, means for engaging the outer ends of said other flaps between said folded portions of the first mentioned flaps, presser arms for straightening said flaps and interlocking said hooks with said slots, and mechanism for operating the parts of said machine.

5. A machine for folding a blank to form a fluid tight carton of the type having a bottom, upwardly folded side walls, corner flaps foldably connected with adjacent side walls and folded and overlapped in pairs against the outer sides of one pair of opposite side walls, one flap of each pair having folded portions receiving therebetween the other flap of the same pair, and interengaging means on said flaps, respectively, for locking said flaps of each pair together, said machine comprising means for folding said side walls upwardly and said corner flaps outwardly, relatively movable devices for oppositely engaging and bending said first mentioned flaps to position the outer ends of said folded portions thereof to receive the ends of said other flaps, means for engaging said other flaps between the folds of the first mentioned flaps, and for interlocking said interengaging means, and mechanism for operating the parts of said machine in timed coordination with each other.

6. A machine for folding a blank to form a fluid

tight carton of the type having a bottom, upwardly folded side walls, corner flaps foldably connected with adjacent side walls and folded and overlapped in pairs against the outer sides of one pair of opposite side walls, one flap of each pair having folded portions receiving therebetween the other flap of the same pair, and interengaging means on said flaps, respectively, for locking said flaps of each pair together, said machine comprising means for folding said side walls upwardly and said corner flaps outwardly, devices for oppositely engaging the first mentioned flaps and positioning the outer ends of said folded portions thereof to receive the ends of said other flaps, means for engaging said other flaps between the folds of the first mentioned flaps, means for laterally engaging and alining said engaged flaps to interlock said interengaging means thereof, and mechanism for operating the parts of said machine in timed coordination with each other.

7. A machine for folding a blank to form a fluid tight carton of the type having a bottom, upwardly folded side walls and corner flaps foldably connected with adjacent side walls and folded and overlapped in pairs against the outer sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising means for folding said side walls upwardly and said corner flaps outwardly, relatively movable devices for folding said top extensions inwardly and downwardly and for positioning the first mentioned flaps to receive the ends of said other flaps, means for engaging the ends of said other flaps between said folded portions of the first mentioned flaps and for interlocking said interengaging means thereof, and mechanism for operating the parts of said machine in timed coordination with each other.

8. A machine for folding a blank to form a fluid tight carton of the type having a bottom, upwardly folded side walls and corner flaps foldably connected with adjacent side walls and folded and overlapped in pairs against the outer sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising means for folding said side walls upwardly and said corner flaps outwardly, relatively movable devices for engaging opposite sides of the first mentioned flaps to fold said top extensions thereof inwardly and downwardly and to bow said flaps outwardly to position the outer folded ends thereof to receive the ends of said other flaps, arms movable laterally of said flaps for engaging said other flaps between said folded portions of the first mentioned flaps and to interlock said interengaging means to secure the flaps of each pair together, and mechanism for operating the parts of said machine in timed coordination with each other.

9. A machine for folding a blank to form a fluid tight carton of the type having a bottom, upwardly folded side walls, corner flaps foldably connected with adjacent side walls and folded and overlapped in pairs against the outer sides of one pair of opposite side walls, one flap of each pair having folded portions receiving therebe-

tween the other flap of the same pair, and interengaging means on said flaps, respectively, for locking said flaps of each pair together, said machine comprising a support for said blank, wings pivoted to swing about parallel axes at opposite sides of said support, respectively, for folding said side walls upwardly and said corner flaps outwardly, devices pivotally mounted on one of said wings to swing about an axis parallel with said wing axis for bowing said first mentioned flaps outwardly to retract and position the outer ends of said folded portions thereof to receive the ends of said other flaps between said folded portions, means for engaging the flaps of each pair with each other to interlock said interengaging means, and mechanism for operating the parts of said machine.

10. A machine for folding a blank to form a fluid tight carton of the type having a bottom, upwardly folded side walls, corner flaps foldably connected with adjacent side walls and folded and overlapped in pairs against the outer sides of one pair of opposite side walls, one flap of each pair having folded portions receiving therebetween the other flap of the same pair, and interengaging means on said flaps, respectively, for locking said flaps of each pair together, said machine comprising a support for said blank, wings pivoted to swing about parallel axes at opposite sides of said support, respectively, for folding said side walls upwardly and said corner flaps outwardly, devices pivotally mounted on one of said wings to swing about an axis parallel with said wing axis for bowing said first mentioned flaps outwardly to retract and position the outer ends of said folded portions thereof to receive the ends of said other flaps between said folded portions, devices pivotally mounted on said wings to swing about axes transversely to said wing axes for engaging the flaps of each pair with each other to interlock said interengaging means, and mechanism for operating the parts of said machine.

11. A machine for folding a blank to form a fluid tight carton of the type having a bottom, upwardly folded side walls and corner flaps foldably connected with adjacent side walls and folded and overlapped in pairs against the outer sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising a support for said blank, wings pivoted to swing about parallel axes at opposite sides of said support, respectively, for folding said side walls upwardly and said corner flaps outwardly, devices pivotally mounted on one of said wings to swing about an axis parallel with said wing axes, for folding said top extensions inwardly and downwardly and for bowing said first mentioned flaps outwardly to retract and position the outer folded ends thereof to receive the ends of said other flaps, means for engaging the outer ends of said other flaps between the folds of the first mentioned flaps, presser arms for straightening said flaps and interlocking said hooks with said slots, and mechanism for operating the parts of said machine.

12. A machine for folding a blank to form a fluid tight carton of the type having a bottom, upwardly folded side walls and corner flaps foldably connected with adjacent side walls and folded and overlapped in pairs against the outer

sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising a support for said blank, wings pivoted to swing about parallel axes at opposite sides of said support, respectively, for folding said side walls upwardly and said corner flaps outwardly, spaced abutments on one of said wings for engagement with said flaps, devices pivotally mounted on the wing having said abutments to swing about an axis parallel with the axis of said wing for cooperation with said abutments to fold said top extensions inwardly and downwardly and bow said first mentioned flaps outwardly to retract and position the outer ends of said first mentioned flaps, means for folding said other flaps inwardly and engaging and pressing the outer ends thereof between the folded portions of the first mentioned flaps to interlock said hooks thereof with said slots, and mechanism for operating the parts of said machine.

13. A machine for folding a blank to form a fluid tight carton of the type having a bottom, upwardly folded side walls and corner flaps foldably connected with adjacent side walls and folded and overlapped in pairs against the outer sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising a support for said blank, wings pivoted to swing about parallel axes at opposite sides of said support, respectively, for folding said side walls upwardly and said corner flaps outwardly, devices pivotally mounted on one of said wings to swing about an axis parallel with said wing axis for folding said top extensions inwardly and downwardly and for bowing said first mentioned flaps outwardly to retract and position the outer folded ends thereof to receive the ends of said other flaps, devices pivotally mounted on said wings to swing about axes transverse to said wing axes, for pressing said flaps toward said side walls to engage the flaps of each pair and interlock said hooks with said slots, and mechanism for operating the parts of said machine.

14. A machine for folding a blank to form a fluid tight carton of the type having a bottom, upwardly folded side walls and corner flaps foldably connected with adjacent side walls and folded and overlapped in pairs against the outer sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising a support for said blank, wings mounted to swing at opposite sides of said support for folding the other pair of side walls upwardly and said corner flaps outwardly and thereby folding the first mentioned side walls upwardly, fingers pivotally mounted on one of said wings for folding said top extensions inwardly and downwardly and for bowing said first mentioned flaps outwardly to position the outer folded ends thereof for receiving the ends of said other flaps, arms pivotally mounted on said wings for pressing said flaps together to engage said other flaps between the folded portions of the first mentioned flaps and interlock said hooks in said slots, a shaft having operating connections with said wings, fingers and arms, and means for rotating said shaft to operate said machine parts.

ends of said other flaps, arms mounted on the ends of said wings to swing about axes transverse to said wing axes to fold and press the flaps of each pair toward said side walls to engage a flap of each pair between the folded portions of the other flap thereof and to interlock said hooks in said slots, and mechanism for operating the parts of said machine.

15. A machine for folding a blank to form a fluid tight carton of the type having a bottom, upwardly folded side walls, corner flaps foldably connected with adjacent side walls and folded and overlapped in pairs against the outer sides of one pair of opposite side walls, one flap of each pair having folded portions receiving therebetween the other flap of the same pair, and interengaging means on said flaps, respectively, for locking said flaps of each pair together, said machine comprising a support for said blank, wings mounted to swing about parallel axes at opposite sides of said support, respectively, for folding the other pair of opposite side walls upwardly and said corner flaps outwardly and thereby folding the first mentioned side walls upwardly, means for folding a flap of each pair thereof inwardly, arms pivotally mounted on one of said wings to swing about an axis extending transversely to said wing axis for folding the other flap of each pair into engagement with the first mentioned flap thereof, means pivoted to swing about said wing axis for moving said arms, arms means for pressing said pairs of flaps inwardly to interlock said interengaging means thereof and mechanism for operating the parts of said machine.

16. A machine for folding a blank to form a fluid tight carton of the type having a bottom, upwardly folded side walls and corner flaps foldably connected with adjacent side walls and folded and overlapped in pairs against the outer sides of one pair of opposite side walls, one flap of each pair having a top extension folded inwardly and downwardly over the top of the other flap thereof with a slot in the line of fold of the first mentioned flap and said other flap having a top hook for interlocking engagement with said slot, said machine comprising a support for said blank, wings mounted to swing at opposite sides of said support for folding the other pair of side walls upwardly and said corner flaps outwardly and thereby folding the first mentioned side walls upwardly, fingers pivotally mounted on one of said wings for folding said top extensions inwardly and downwardly and for bowing said first mentioned flaps outwardly to position the outer folded ends thereof for receiving the ends of said other flaps, arms pivotally mounted on said wings for pressing said flaps together to engage said other flaps between the folded portions of the first mentioned flaps and interlock said hooks in said slots, a shaft having operating connections with said wings, fingers and arms, and means for rotating said shaft to operate said machine parts.

65 WILLIAM H. INMAN.
